UNITED STATES PATENT OFFICE

GEORGE VOELKER, OF ST. PAUL, MINNESOTA.

TYPE-WRITING MACHINE.

1,128,736.

Specification of Letters Patent. Patented Feb. 16, 1915.

Application filed September 14, 1909. Serial No. 517,758.

To all whom it may concern:

Be it known that I, GEORGE VOELKER, a citizen of the United States, residing at St. Paul, in the county of Ramsey and State of Minnesota, have invented certain new and useful Improvements in Type-Writing Machines, of which the following is a specification.

My invention relates to improvements in typewriters of the class having a laterally moving or driven platen carriage, which is freed or released from its escapement devices by actuating a tabulator key or otherwise, and in which the writing mechanism is set in motion and caused to print an impression by the depression of a key or key lever.

Where, as is now usual in machines of this class, lines or rows of dots, dashes, or other characters can only be made by successively depressing and releasing the key or key lever for each character in the row, an unnecessary amount of time and energy is wasted, and the usefulness of the machine is effectually limited because of the danger of confusion if the lines are omitted, and the waste of time if the lines of dots or dashes have to be made by repeatedly and successively depressing the key. This is particularly the case in the billing of goods, where the items are arranged in columns at the extreme left of the sheet and the charges at the extreme right of the sheet. If the intervening space is left blank the reader, in endeavoring to select a particular item and its cost, often resorts to a ruler to guide the eye, while the use of a line of dots or dashes to connect the item and its cost is forbidden on account of the consumption of time and energy.

It is the object of the present invention to provide improved means for writing lines consisting entirely or in part of a succession of dots, dashes, or other characters, in rapid succession, by simply holding depressed one or more key levers and preferably by causing this to be done automatically in the ordinary power driven travel of the carriage to the left, or, in other words, to cause the characters to be written from left to right as in ordinary writing.

A further object of the invention is to provide means for instantly changing the activities of the machine from writing ordinary matter to automatically running off a line, or part of a line, of dots, dashes, or

other characters, and then, at any desired point, instantly resuming the writing of matter in the ordinary way.

A further object is to provide means whereby the lines of dots or dashes can be made with sufficient power to make a suitable impression upon the waxed sheets or other plates to be used for stencils.

More particularly the invention consists in the features of construction, combination and arrangement of parts hereinafter described and claimed.

In the drawings I have shown the invention applied to an L. C. Smith & Bro. typewriting machine, but it is to be understood that the invention may be embodied in other styles of machines.

Referring now to the accompanying drawings forming part of this specification Figure 1 is a perspective view of the invention applied to a machine, which is shown in dotted lines and partly broken away; Fig. 2 is a similar view, showing the parts in different relations; Fig. 3 is an enlarged perspective view of a type bar; Fig. 4 is a perspective view of a typewritten sheet, showing several kinds of writing executed with the invention; Fig. 5 is a perspective rear view of a portion of the invention partly broken away; Fig. 6 is an elevation of the rocking arm; Fig. 7 is a plan view of the same; Fig. 8 is a sectional view on line $x-x$ of Fig. 7; Fig. 9 is a plan view of the latch casing containing the latch; Fig. 10 is an end view of the same; Fig. 11 is a sectional view on line $y-y$ of Fig. 10; Fig. 12 is a perspective view of the rocking arm stand; Fig. 13 is a side elevation of the latch and spring actuating mechanism; Fig. 14 is a front elevation of the same; Fig. 15 is a plan view of the rocking arm showing the latch open; Fig. 16 is a plan view of the same showing the latch closed; Fig. 17 is a perspective view of the swinging pawl and its supporting bracket; Fig. 18 is a front elevation of the swinging pawl showing its relation to the toothed driving wheel; Fig. 19 is the same showing the parts in different relations; Fig. 20 is a side elevation of the key and controlling lever; Fig. 21 is a side elevation of the connecting rod; Fig. 22 is a plan view of the same; Fig. 23 is a diagrammatic view of some of the type bar, carriage, ribbon and escapement actuating mechanism of an L. C. Smith & Bro. machine; Fig. 24 is a perspective view of a

fragment of the machine showing the carriage, the spring and drum for driving the same, and the tabulator mechanism, and Fig. 25 is a detail of the tabulator dog.

5 As shown in Figs. 1, 23 and 24 of the drawings A represents the frame of a typewriting machine, B the platen, C the carriage, D the gear rack attached to the carriage, and E the usual pinion keyed on the escapement wheel shaft in mesh with the rack. The carriage and rack are connected with the usual power drum 83 and its actuating spring 84, by means of a strap 85 secured at one end upon the periphery of 10 the drum and at the other end to the end of the carriage which is farthest away from the drum. G represents the printing ribbon, and F the guide plate therefor. The guide plate is connected with a reciprocating means, as shown in Fig. 23, consisting of the levers H, I, J, K, the link L and the bell crank N, through the medium of which it is operated. The guide plate F serves as a ribbon carrier and reciprocates in an approximately vertical plane in front of the platen B, carrying with it the ribbon G. The usual type-bars of the machine, as well as the vibratory type-bar X of my invention, are arranged forwardly of the platen, which they 20 strike from in front centrally of the guide plate. O represents one of the usual type bars and $a^1, a^2, a^3, a^4, a^5, a^6$ are pivotal bearings in the frame A. P is the escapement wheel and Q the escapement shaft. R represents 30 the tabulator bar or key which, when depressed, releases the carriage by means of mechanism hereinafter described. S represents the usual spacing bar or key.

All the parts mentioned above have reference to the well known L. C. Smith & Bro. typewriting machine, and need not be more particularly described, except so far as a more detailed description may be necessary to understand the relation of my invention 45 thereto.

Referring to the drawings, the invention comprises several coöperating groups of mechanism, among which are the swinging pawl-driving mechanism V, the rocking 50 arm, gripping and controlling device W, the linked type bar X, and the operating key Y. These are arranged in such coöperative relation to the machine as to cause the printing instrumentalities to strike the platen in front. To accomplish this the power to actuate the type bar is taken from a point behind the platen and carriage, transmitted around the necessary angles and underneath the carriage to a point in front 55 of the platen. In carrying out the invention I take the power from the spring drum indirectly through the carriage and escapement shaft, as will be hereinafter explained, instead of from the spring drum direct.

65 Referring now to Figs. 5, 17, 18, and 19,

the pawl driving mechanism V comprises a toothed device or notched wheel 2 mounted rigidly on escapement shaft Q, and a supporting bracket 4 having a base 5 fastened to the frame, a journal box 6 at its top, and a stop pin 7 intermediate of its height. Carried by the bracket is a drop hanger 8 having parallel upper and lower journal shafts 9 and 10, respectively, the journal shaft 9 having bearings in the journal box 6, and the lower shaft 10 having its bearing in the pawl 15 hereinafter described. The journal shaft 10 terminates in a screw threaded portion fitted with stop and lock nuts 12 and 13, respectively. Rotatable upon the shaft, and provided with a stop pin 14 above and parallel with said shaft, is a pawl lever 15, which has spring connection 17 with the hanger bar 8, the spring 17 consisting of a wire coil having divergent legs 18 pivotally connected, one with the hanger bar, and the other with the outer end of the pawl lever. The spring tends to draw the legs 18 toward each other, and thus normally keeps the acting end of the pawl in 90 downward position, as shown in Figs. 17 and 19, in the path of the notched wheel 2.

As shown in Figs. 5, 21, and 22, the transmission rod 19 has at one end a block 20 pivotally mounted on the shaft 10 and 95 slide longitudinally between the guides 21 of the head 22 of the rod. This block can be adjusted longitudinally by means of an adjustment screw 24 threaded through the end wall of the head 22 and having swivel 100 connection 23 with the block.

The group of mechanism which I have called the rocker arm, gripping and controlling device W, as best shown in Figs. 5 and 12, comprises a stand 25 having a base 105 portion 26 fastened to the frame A, a studded top 27 and an offset intermediate lug 28 carrying rigidly a rearwardly extending pin 29. The stud 30, which is fast to the top 27 forms a journal shaft for the 110 rocking arm 31 journaled upon it by means of the bearing 32 which is arranged at the juncture of the radial arms 33 and 34. Thus these arms form a bell crank. The arm 33 terminates in a gripping device consisting of an open V-shaped jaw 35 within which works a laterally moving spring controlled latch 36. This latch and its controlling spring are incased in a sectoral sliding member 37 which slides within a guide 115 38 arranged on the underside of the rocking arm 31, and preferably integral therewith. The arm 34 has at its outer end an upwardly extending finger 39 which is connected by means of the spring 50 with a lever arm 49, hereinafter mentioned, and is formed intermediate of its length with a hole 40, within which is rotatably received the downturned journal pin 41 of the transmission rod 19. As will be seen from Figs. 120 125 130

9, 10, and 11, the sectoral sliding member is formed interiorly with two stop lugs 42 which project into the latch chamber 43 and form an abutment for the enlarged end 44 of the latch when the same is in its normal position. It is held normally in extended position by means of a retaining spring 45 coiled about the stem of the latch and abutting against the lugs 42 of the latch casting 37, and the shoulders 46 of the latch.

Secured to the stud 30 by means of set screw 47 is a downwardly and rearwardly extending journal arm 48 upon which is pivotally mounted the lever arm 49, the outer end of which is elastically connected with the spring 50 by means of the spring 51. The inner end of the lever 49 terminates in a nose 51 as best shown in Fig. 44. Pivotally mounted on the journal pin 29 is a bell crank 52 having a forked end 53 which straddles the segmental guide 55 of the sectoral sliding member 37, said guide being concentric with the stud 30. Between its ends the bell crank 52 has an upwardly and rearwardly extending cam lug 53 which engages the nose 51 of the spring lever 49. The other leg of the forked bell crank affords pivotal connection 56 for the connecting rod 57, which at its other end has pivotal connection 58 with the bell crank 52, as best shown in Fig. 5. This bell crank is pivotally supported upon a drop bracket 60 which is fastened to the frame A by means of a screw 61. Pivotally connected to the downwardly extending arm of the bell crank 52 is a controlling lever 62 which extends to the front of the machine, where it has pivotal connection 63 with the lower or downward leg of the controlling lever 64. The controlling lever is pivotally mounted near its upper end on the key disk 65 by suitable means such as the ears 66 and journal pin 67, and has at its upper end an obliquely arranged finger plate 68 extending over the key disk 65 and provided on its underside with a spring retaining lug 69 which holds in position the spring 70 interposed between the finger plate 68 and the key disk 65.

The instrumentality hereinbefore called the hooked type bar X is constructed in the shape, generally speaking, of a bell crank, comprising a frame 72 having at one end pivotal connection 73 with the rearwardly extending link 74, and at the other end a type holding extension piece 75, and having intermediate of these ends an out-projected portion 71, shown in dotted lines in Figs. 2 and 3, which has pivotal bearing 76 similar to the usual pivotal connections of the type bars in the basket of a front strike machine such as is here shown. The type holding end 75 of the type bar X terminates in a pair of type ends 76 and 77. These type ends are arranged with refer-

ence to the frame 72 so as to strike the ribbon centrally of the ribbon guide F, that is to say, in the same place that is struck by the ordinary type bar of the machine. The driving link 74 has at its forward end a 70 downturned journal end 79 which forms the pivotal connection 73 with the type bar X, and at its rear end a downturned journal end 78, which is in position to enter the V-shaped jaw 35 when the type bar X is raised 75 to printing position. The link is guided in its movement by passing slidably through a hole 80 in the frame A.

In Fig. 24 is shown the carriage, carriage driving spring drum, and tabulator mechanism of an ordinary L. C. Smith & Bro. typewriter machine, such as is illustrated in Figs. 1, 2 and 3. As these parts, and their operation, are well known in the art no extended description of them is necessary. 80 The tabulator comprises a group of mechanism extending from the key board to the rear of the machine, where it operatively engages the dog 86 carried by the lever K pivotally mounted in the frame, as shown in Fig. 23, in 85 position to engage the escapement wheel P. This group of mechanism comprises a rock shaft 87 carrying a pair of forwardly extending arms which support the tabulator bar or key R. The rock shaft is journaled 90 in the frame A, and has a downwardly projecting crank arm 88 which is connected by means of the link 89 with the wiper arm 90 at the rear of the machine. This wiper arm is journaled on the frame at 102, and its 105 outer end engages the crank arm 91 of a rotatable shaft 92. Upon this shaft is a forwardly extending crank arm 93 which is connected by means of a vertical link 94 with the double-armed or U-shaped lever 108 95, which is pivotally supported intermediate of its ends on the pivots 96 upon the underside of the top plate of the frame A. One of the arms 97 of this lever normally rests on the tooth 98 of the dog 86. Thus, 110 when the bar or key R is depressed it will, through the medium of the mechanism just described, depress and turn the dog upon its supporting pivot 99 out of engagement with the escapement wheel, and thereby release 115 the carriage. The dog is kept in normal position in the path of the escapement wheel by means of the spring 100, and is prevented from further upward movement by means of a lug 102 carried by the lever K in position 120 to be engaged by the lip 101 of the dog 86. Fig. 24 shows the position of the parts when the key lever Y has been depressed to bring the lever K to the same position as shown in dotted lines in Fig. 23. When the parts are in this position, as is clearly shown in Fig. 24, the escapement wheel, and therefore the carriage, is held by the dog 86 alone, so that when the tabulator key or bar is depressed the carriage will be released. 125

In Fig. 2 of the drawings the parts are shown in their normal position when out of use, while in Fig. 1 they are shown in the position assumed by them when the key lever J is depressed by the operator. As will be there seen, when the plate 68 is depressed against the pressure of its spring 70 the controlling lever 64 will be turned so as to actuate the forked bell crank 52 through the medium of the rod 62, bell crank 59, and rod 57. When the bell crank 52 is thus turned, its forked end 54 will push the latch 36 and its casing 37 in the direction of the jaw 35 and thereby block the entrance to the same, as shown in Figs. 7 and 16, leaving an opening 81, however, to receive the journal end 78 of the link 74. At the same time the bell crank 52 also actuates the spring lever 49 by means of its projecting cam lug 53, which engages the nose 51 of the spring lever. In this movement the latch 36, the rocking arm 31, and the spring 50 will have changed from the position shown in Fig. 15 to that shown in Fig. 16. This is accomplished by the depression of the plate 68 before the depression of the key lever J has begun. The rotation of the rocking arm 31 about the stud 30 is effected by the movement of the spring lever 49 in that it shifts the line of force in the spring 50 from one side to the other over the stud 30, or in other words dead center. The segmental guide 55, being concentric with the stud 30, will move between the tines of the forked end 54, and thus permit lateral movement of the latch and its casing while the rocking arm 31 is in motion.

Another movement effected by the depression of the plate 68, through the medium of the rocking arm 31, is the forward and upward movement of the transmission rod 19 owing to its pivotal connection 40 with the rocking arm. When thus moved, the transmission rod will communicate its motion to the drop hanger 8, and cause the hanger to swing forward and rotate about its upper journal bearing 9, carrying with it the pawl 15 which is pivotally mounted on the lower journal shaft 10, until the hanger bar engages, and is stopped by, the pin 7. During this movement the pawl is held with its stop pin 14 pressed against the hanger, by means of the spring 17. This upward and forward movement, it will be seen, has changed the position of the pawl 15 from its normal position shown in Fig. 5, wherein it is drawn out of range of the toothed wheel 2, to that shown in Fig. 19, wherein it is forced forward into the path of the toothed wheel as the wheel turns in the direction of the arrow. The functions then of the controlling lever 64 may be summarized as follows: First: Its depression by the operator changes the position of the parts from that

shown in Figs. 4 and 15 to that shown in Figs. 1, 7, 14, 16, 18, and 19. In other words it throws the machine into gear, with the pawl 15 in the path of the toothed wheel 2, and prepares the latch and gripping device for the reception of the downturned end 78 of the link 74. Secondly: Its release from pressure by the operator permits the spring 70 to expand and turn it back into normal position, thereby restoring the forked bell crank 52 and its cam lug 53, and also the latch and its casing to their normal position, but the spring lever 49 will remain in the position shown in Fig. 14, since the cam lug 53, upon being restored, simply recedes from the contact nose 51, and leaves the spring lever 49 unmoved. It will be evident, therefore, that the rocking arm 31, transmission rod 19, hanger 8, pawl 15, and spring 50, which depend upon the lever 49 for restoration to normal position, will also remain unmoved, and will retain the positions shown in Figs. 1, 13, 14, 16, 17, 18, and 19, except that the latch and its casing 37 will have been restored to normal position through the movement of the segmental guide 55.

The restoration of the spring lever 49 and the above named parts depending on it occurs as follows: It will be remembered that pawl 15 is still "in gear," that is in the path of the toothed wheel 2, because the lever 49 still holds the spring 50 to the left of dead center (stud 30). And even if the operator of the machine trips the usual carriage release lever and pulls the carriage to the right to start a new line, thereby reversing the direction of the toothed wheel 2, the above mentioned unrestored parts will still remain unmoved except that the pawl will ride over the teeth of the wheel 2 against the tension of its spring 17, as shown in Fig. 18. But when the operator begins to write by manipulating the keys, the escapement shaft and the toothed wheel 2 will now turn in the other direction, namely to the right, as shown in Fig. 19, and will engage and kick back the pawl 15, which is still in range. The impulse thus given the pawl will be transmitted through the rod 19 to the rocking arm 31, thereby turning this arm until the spring 50 passes dead center and draws the lever 49 back to its normal position. When thus restored the lever 49 will hold in restored position all of the above named parts depending on it.

The foregoing explanation refers only to the results obtained by the depression of the finger plate 68, it being assumed that the plate has not been so far depressed as to exert pressure enough to actuate the key lever J. If, after depressing the plate 68 to the limit of pivotal movement, the operator continues the pressure so as to depress the

key lever J he will set in motion the usual mechanism employed to actuate the usual type bar.

In the diagrammatic view (Fig. 23) of 5 an L. C. Smith & Co. typewriting machine, the dotted lines indicate the position the parts will assume when the type bar O will have been raised to a position about midway of its full course. If, however, the lever J were still farther depressed and the type of the type bar struck the platen B, the lever K would have moved to the right until it was in full engagement and alignment with the escapement wheel P, and thus hold the carriage C, and therefore the platen B, in locked position during the time that the type was in contact with it. This is a common feature in ordinary typewriting machines, namely, momentarily to 20 lock the platen carriage with every stroke of the type bar in order to insure clear and sharp impressions of the type and to avoid blurring.

In the practice of my invention I cut out 25 the locking and unlocking of the carriage in the following manner: In Fig. 23 the lever K is shown just clearing the escapement wheel P, and the type bar O has traversed part of its course to the platen, but 30 still has a considerable distance to travel to finish its stroke, leaving a large gap S2 between the type bar and the ribbon and platen. It will be evident that if this midway position of the type bar O, shown in 35 dotted lines, were the limit of its upward movement, the lever K would also be limited in its movement, making its engagement with the escapement wheel, and therefore the locking of the carriage, impossible. In 40 my invention I have spanned this gap S2 by means of a type bar extension 75 which carries at its outer end the type desired, such as the period 76 and dash 77 shown in the drawings. Thus by the use of the extension 75 the type end of the bar X may 45 be brought close to, and even in actual contact with, the platen without moving the lever K into engagement with the escapement wheel, and therefore leaving the 50 platen still free to move to the left when the tabulator key is depressed as hereinafter explained.

It will be seen from Fig. 23 that when the lever J has been depressed sufficiently to 55 bring the type bar O into the position shown in dotted lines it will also have raised the guide F with its ribbon G to be raised, through the medium of levers I, K, L, link M, and bell crank N, into the path 60 of the type at the end of the type bar. In Fig. 9 the type bar X is shown in its normal or "out of use" position. When the key lever J is depressed, the type bar X is 65 lifted to printing position as shown in Fig.

1, dragging after it, through the guide hole 65 80, the link 74, the downturned journal end 78 of which will enter the V-shaped jaw 85, push back the spring retained latch 86, and enter the opening 81, while the latch, returning under pressure of the spring 85, 90 will block the jaw 85, and thus effectually confine the journal end 78 in the opening 81, but without preventing it from rotating therein. Upon releasing the lever J from pressure, and also releasing the controlling 95 lever 64, the latch 86 will return, through the medium of the bell crank 82, to its normal open position and the type bar 72 and link 74 will fall back into the normal position shown in Fig. 2, the type bar being actuated by the same returning means that is applied to the other type bars of the machine.

To operate a typewriting machine embodying my invention, and to produce lines 85 of dots, dashes, or other characters, such as is shown in Fig. 4 of the drawings, the operator first depresses the key Y to its downward limit and holds it down as long as it is desired to write such dots, dashes, or 90 other characters. It will be understood that by reason of the extension 75 of the type bar X the lever K has not been carried into engagement with the escapement wheel, so that the carriage is held only by the dog 86 95 of the tabulator mechanism. With the other hand the operator then depresses the tabulator key or bar R. This will cause the arm 97 of the lever 95 to turn the dog 86 out of engagement with the escapement 100 wheel. The carriage C and its rack D, being thus released, will be drawn rapidly to the left by the spring actuated drum 83, the rack D in its travel driving the toothed wheel 2 through the medium of the pinion 105 E and the shaft Q. The teeth of this wheel will engage the pawl 15 in rapid succession, thus intermittently actuating or vibrating it as the wheel turns in the direction of the arrow in Fig. 19, the pawl returning after 110 each tooth driven impulse by virtue of the spring 56. These vibrations will be transmitted through the rod 19, rocking arm 31, and link 74, to the type bar X, which will thus be made to strike the ribbon with every 115 impulse, and print a succession of dots or dashes on the paper carried by the platen, which, owing to its release, is rapidly passing the striking point behind the ribbon.

The force of the blow struck by the type 120 end can be varied at will by changing the length of the transmission rod 19 and thus bringing the type ends of type bar X nearer to, or farther away from, the platen, as the case may be. This is accomplished by turning the adjustment screw 24 so as to cause the block 20 to slide between its guides, as heretofore explained. At the same time the 125

speed of the carriage will be controlled by the force of the blow, because the harder the type strikes the platen the greater will be its retarding effect thereon. It will be 5 obvious that where the work in hand permits the dots to be run to the end of a line, a higher rate of speed can be used than in work where the operator must stop the carriage in the middle of a line by releasing 10 the tabulator key. In such case the speed of the carriage can be reduced by lengthening the transmission bar so as to increase the force of the blow and thereby increase the resistance of the type bar to the left- 15 ward movement of the platen. If, now, the transmission rod 19 is shortened sufficiently to prevent the type ends from reaching the platen, the type bar X will be rendered ineffective to print, and the only effect of operating the key lever J will be to cause the pawl 15 and the mechanism operatively connected with it to serve as retarding means for retarding the free run of the carriage 20 when the carriage is released from the control of the escapement mechanism, the pawl acting as a drag upon the toothed wheel 2 which turns with the pinion E. This is particularly useful in tabulating work where long runs of the carriage are necessary. 25

It will be seen that by the mechanism here shown I use the power driven travel of the carriage to the leftward, that is in the direction of its feed, to force the type bar X against the platen, so that I get 30 into the blow the power of the carriage-impelling force, and so that the dots are run off automatically at any place in the work by merely holding two keys depressed for the length of time desired. When the keys 35 are released the dots will instantly cease and the writing of words can be resumed. The invention, however, is not limited to automatic writing, for, when the key Y is depressed with one hand, the carriage and 40 usual release lever Z can be grasped with the other hand and drawn back and forth at will, whereby a line of dots or dashes is written with every trip of the carriage to the left. When manual force is thus used 45 to operate the carriage, the transmission bar 19 can be adjusted to strike a harder blow than would be possible where the power driven travel of the carriage is used, because the force of the carriage-driving 50 power is limited, but sufficient manual force can always be supplied according to the needs. This capability of causing very hard blows to be struck when the carriage is operated by hand is especially useful in 55 making stencils where the type must be driven into the waxed sheet or stencil plate.

It will be seen that the type ends 76 and 60 77 are separated by a distance corresponding to the distance between the capitals and small letters of the usual type bar. To use

one of the type ends the usual shift key must be used.

It is obvious that the details of the device may be variously modified without departing from the principle of the invention, the scope of which is defined in the claims. 70

I claim as my invention:

1. In a typewriting machine the combination with a power driven carriage, of a vibratory type, a vibrator therefor actuated 75 by the movement of the carriage in the direction of its feed, and means for controlling the vibrator.

2. In a typewriting machine, the combination with a power driven platen carriage and escapement mechanism and means for releasing the carriage from the escapement, of a reciprocator device operatively connected with a type holding device and with a means for placing said reciprocator device 80 into operating position, the reciprocator device being arranged to be actuated by the carriage when it is released from the escapement.

3. In a typewriting machine, the combination with the carriage and escapement mechanism and means for releasing the carriage from the escapement, of a vibrator device and a controlling mechanism, and a movable type holding device operatively 85 connected to both, said vibrator device being arranged to be actuated by the carriage, when it is released from the escapement.

4. In a typewriting machine, the combination with the carriage and escapement 90 mechanism and means for releasing the carriage from the escapement, of a controlled reciprocating means, said means actuating a type bar and being arranged to be actuated by the carriage, when said carriage is 95 released from the escapement.

5. In a typewriting machine, the combination with the carriage and escapement mechanism and means for releasing the carriage from the escapement, of a reciprocator device, a diverting transmission device operatively connected therewith, a movable type holding device operatively connected with said transmission device, and a controlling means operatively connected with said reciprocator device, said reciprocator device 110 being arranged to be actuated by the carriage when it is released from the escapement.

6. In a typewriting machine, the combination with the carriage and escapement mechanism and means for releasing the carriage from the escapement, of a reciprocator device operatively connected with a type bar and controlling means, said reciprocator device being arranged to be actuated by the carriage when it is released from the escapement, said carriage actuating said reciprocator when moving in one direction only. 120

7. In a typewriting machine, the combination with the carriage and escapement mechanism and means for releasing the escapement, of a power driven type bar connected with driving mechanism actuated by the carriage when it is released from the escapement, said driving mechanism having operative connection with controlling means.
8. In a typewriting machine, the combination with the carriage and escapement mechanism and means for releasing the escapement, of a power driven type bearing printing arm, and controlled power transmitting means, said means becoming operative when the carriage is released from the escapement.
9. In a typewriting machine the combination of a carriage having a platen, a rack carried by and movable with the carriage, a type bearing printing arm intermittently actuated by said rack to force the type arm against the platen when the carriage is moved to the left, and means for moving the carriage to the left.
10. In a typewriting machine, the combination with the carriage and escapement mechanism and means for releasing the escapement, and ribbon vibrating means, of a power driven writing means, means for cutting off or connecting with the source of said power, said power being applied in one direction by releasing the carriage from the escapement.
11. In a typewriting machine, the combination with the carriage and escapement mechanism, means for releasing the escapement, and the type bar actuating means, of a hand operated controlling means, a type bar, and a power transmitting device, said type bar and transmitting device being moved into operative position by said controlling means, the power being transmitted to the type bar, when the carriage is released from the escapement.
12. In a typewriting machine, the combination of a carriage, means for impelling said carriage in one direction, carriage escapement devices, a tabulator key operative to free the carriage from its escapement devices and to permit said carriage to move freely to a predetermined point, a vibratory ribbon guide, a power driven type bar, a power transmitting device communicating with said type bar, a hand operated controlling means to set the transmitting device and the type bar into power receiving position, said transmitting device being arranged to be actuated by the carriage when it is released from the escapement.
13. In a typewriting machine, the combination of a carriage, means constantly tending to impel the carriage in one direction, carriage escapement devices, means for releasing the carriage from its escapement devices, said means including a releasing lever, ribbon oscillating mechanism, a reciprocator device operatively connected with a type holding printing arm; a controlling device to set the reciprocating device and printing arm into starting and stopping position, said reciprocator device being arranged to be actuated by the carriage when it is released from the escapement.
14. In a typewriting machine, the combination of a carriage, means tending to drive the carriage in one direction, carriage escapement devices, means for releasing the carriage from said escapement devices, a vibratory ribbon carrier, type printing or writing means, power applying means to said type printing or writing means, and means for preparing the said power applying and printing or writing means to receive impulses delivered by the carriage when it is released from the escapement.
15. In a typewriting machine, the combination of a platen-carriage, a vibratory ribbon carrier and ribbon arranged in front of the platen, a vibratory type, and means actuated by the carriage in its leftward travel for vibrating the type against the ribbon and platen.
16. In a typewriting machine, the combination with a movable carriage, of a locking device to check the leftward movement of the carriage, means for releasing the carriage from the locking device, a vibratory printing instrumentality actuated by a movement of the carriage in the direction of its feed, and a key controlling said printing instrumentality to render the same operative when the carriage is so moved.
17. In a typewriting machine, the combination with a movable platen and escapement mechanism wherefor including an escapement shaft, of a toothed wheel mounted on the escapement shaft, a type bar, a vibrator arranged at the rear of the platen and adapted to be moved into or out of engagement with said toothed wheel, and means for operatively connecting said vibrator and type bar.
18. In a typewriting machine the combination with the carriage and its platen, of a bell crank type bar having one arm extended up at the front of the platen and the other arm extended downwardly and having intermediate offset pivotal support, a vibrator arranged at the rear of the platen in position to be actuated by the carriage in its movement, and mechanism operatively connecting the down-turned arm of the bell crank type bar with the vibrator.
19. In a typewriting machine the combination of a movable platen, a vibratory ribbon carrier in front of the platen, a vibratory type controlled by the movement of the platen, means actuated by the movement of the platen for vibrating the ribbon carrier and also for vibrating the type in the

direction of said carrier when said platen is moved and a controlling means for the moving of the platen.

20. In a typewriting machine the combination with a power driven carriage, of a vibratory type, a vibrator therefor actuated by the movement of the carriage in the direction of its feed, and means for controlling the vibrator.

10 21. In a typewriting machine, the combination with a driven platen carriage and escapement mechanism therefor, of means for automatically actuating a typewriting mechanism, means for releasing the carriage from the escapement mechanism, and means for controlling said actuating mechanism.

22. In a typewriting machine, the combination with a driven platen carriage and escapement mechanism and means for releasing the carriage from the escapement, of means for producing a reciprocating motion when actuated, a type holding device operatively connected with said reciprocating motion producing means, said type holding device being adapted to hold separated the carriage and its escapement, and a controlling means, said elements being so arranged that the reciprocating motion producing means will be actuated when the carriage is released from the escapement.

23. In a typewriting machine, the combination with a carriage and escapement mechanism and means for releasing the escapement, of an automatically actuated and hand controlled type writing or printing device having operative connection with means for releasing the escapement.

24. In a typewriting machine the combination of a vibratory type, vibrator mechanism therefor, a carriage and escapement devices therefor, a key board, a tabulator key in the key board to release the carriage from its escapement device to cause it to travel to the left, and a controlling key for the vibrator mechanism, the parts being arranged so that the depression of the controlling key alone will cause the type to make an imprint for each depression thereof, but the simultaneous depression of both the tabulator and controlling keys will cause the type to make a plurality of imprints.

25. In a typewriting machine, the combination with a carriage and its platen, and escapement mechanism therefor, of type bars operatively connected with the escapement mechanism so as to check the movement of the carriage when one of said type bars is actuated, and a similarly connected type bar arranged in front of the platen, said bar having means whereby its operative connections are prevented from engaging the escapement mechanism when it is moved against the platen.

26. In a typewriting machine, the combination with a driven carriage having a

platen and an escapement and releasing device therefor, of a controlled mechanism including a type and a toothed wheel, a key for releasing the carriage from its escapement and causing it to turn said wheel, and connections between said wheel and type to cause the type to contact with the platen.

27. In a typewriting machine, the combination of a driven device having a platen, locking mechanism therefor, typewriting instrumentalities including a type and a toothed device operatively connected with said driven device, means for releasing said driven device from its locking mechanism and connections between said toothed device and type to cause the type to contact with the platen.

28. In a typewriting machine, the combination with a movable platen carriage, of a vibrator arranged at the rear of the carriage in position to be actuated by the carriage in its travel, a type-bar arranged at the front of the carriage, a link pivotally connected with the type-bar and standing normally out of engagement with the vibrator, and means for carrying the link into engagement with the vibrator when the type-bar is actuated.

29. In a typewriting machine, the combination with a movable platen carriage, of a vibrator arranged in position to be actuated by the carriage in its travel, a gripping device in position to be engaged by the vibrator, and a keyed type-bar in position to be thrown into operative engagement with the gripping device when its key is actuated.

30. In a typewriting machine, the combination with a movable platen carriage, of a vibrator in position to be actuated by the carriage in its travel, a type bar movable to operative position from the front of the machine, and an adjustable connection between the type bar and the vibrator, whereby the printing end of the type bar may be set nearer to, or farther away from, the platen.

31. In a typewriting machine, the combination with a movable platen carriage, of a vibrator in position to be actuated by the movement of the carriage in the direction of its feed, a type bar operatively connected with the vibrator, and means for adjusting the normal position of the printing end of the type bar toward or away from the platen.

32. In a typewriting machine, the combination with a movable platen carriage, of a vibrator in position to be actuated by the movement of the carriage in the direction of its feed, a type bar, and a connection adjustable in length between the type bar and the vibrator, whereby the printing end of the bar can be set at different distances from the platen.

33. In a typewriting machine the combination with a carriage, keys and key actu-

ated type bars, of a pivoted skeleton frame, a type holding extension piece on said frame said piece extending toward the printing point, a pivotal connection in said frame, 5 and means between said connection and said carriage for actuating said frame by moving the carriage to the left.

34. In a typewriting machine, the combination with a movable platen carriage, of a 10 vibrator, a gripping device, a transmission rod adjustable in length between the vibrator and the gripping device, and a keyed type bar adapted to engage the gripping device when its key is operated.

35. In a typewriting machine, the combination with a movable platen carriage and a type bar, of a toothed wheel actuated by the carriage in its travel, a swinging pawl in position to be engaged by said wheel, a 20 breakable connection between the pawl and the type bar, and spring means actuated by the pawl, when kicked back by the wheel, for holding the pawl normally out of engagement with the wheel.

36. In a typewriting machine, the combination with a movable platen and escapement mechanism therefor, of a toothed wheel driven by the escapement mechanism, vibrator mechanism standing normally out of 20 engagement with said toothed wheel, but adapted to be moved into engagement with it, a type bar, and means operatively connecting said vibrator mechanism and type bar.

37. In a typewriting machine, the combination with a platen carriage and its escapement shaft, of a toothed wheel keyed to the escapement shaft, a type bar, a gripping device engageable with the type bar, a 40 spring pawl having swinging support near the toothed wheel, a connection between the pawl and the gripping device, and spring means actuated by the backward kick of the toothed wheel against the pawl for holding the pawl normally out of engagement with the wheel.

38. In a typewriting machine the combination with a movable platen carriage and locking devices therefor, of a vibratory type 50 bar, mechanism actuated by the carriage in its travel for vibrating said type bar, and means operated from the keyboard for releasing the carriage from its locking devices and also for moving the type bar to printing position.

39. In a typewriting machine, the combination with a platen carriage, of a vibratory type, a vibrator therefor including a swinging pawl actuated by the movement of the 60 carriage in the direction of its feed, and means for controlling the vibrator.

40. In a typewriting machine, the combination of a platen carriage, a vibrating ribbon carrier and ribbon arranged at the front 65 of the platen, a vibratory type, means op-

erated from the front of the keyboard for moving both ribbon and type into printing position, and means actuated by the carriage in its leftward travel for vibrating the type against the ribbon and platen.

41. In a typewriting machine, the combination of a printing instrumentality, power operated means for actuating said printing instrumentality, a tabulator, and means controlled by said tabulator for rendering operative 70 said actuating means for the printing instrumentality.

42. In a typewriting machine, the combination of a power driven carriage, a printing instrumentality, means controlled by the 80 power employed to move the carriage for actuating said printing instrumentality, tabulator mechanism, and means controlled by said tabulator mechanism for rendering said printing instrumentality actuating 85 means operative or inoperative.

43. In a typewriting machine, the combination of a carriage, a printing instrumentality, means for intermittently actuating said printing instrumentality during the 90 travel of the carriage in the direction of its feed, tabulating mechanism, and means controlled by said tabulating mechanism for rendering said intermittently actuating means operative or inoperative.

44. In a typewriting machine, the combination of a power driven carriage, a type bar, actuating means controlled by the carriage for intermittently actuating said type bar during the free travel of the carriage in 100 the direction of its feed, tabulating mechanism, and means controlled by said tabulating mechanism for rendering the actuating means operative or inoperative.

45. In a typewriting machine, the combination of a carriage, escapement devices for the carriage, tabulating devices, a type carrier, actuating means for operating said type carrier, and means for taking the carriage 105 out of the control of the escapement devices and placing it under control of the tabulating devices and for simultaneously rendering said actuating means operative.

46. In a typewriting machine, the combination of a power driven carriage, escapement devices for the carriage, tabulating devices, a type carrier, actuating means for operating said type carrier, said actuating means being controlled by the power employed to move the carriage, and means for taking the carriage out of the control of the escapement devices and placing it under control of the tabulating devices and for simultaneously rendering said actuating means 115 operative.

47. In a typewriting machine, the combination of a carriage, tabulating mechanism, a type bar, key actuated means for moving the type bar to printing position, actuating 120 means for vibrating said type bar when it is 130

- 13 moved to printing position by said key, and
means under control of said tabulating
mechanism for rendering said actuating
means operative.
5. 48. In a typewriter, the combination with
a carriage, and letter-spacing mechanism
engaged thereby, of mechanism normally
disconnected from the carriage for oscillat-
ing the type-carrier bodily when at the
10 printing point, and a key-controlled lever
having means for moving the type-carrier
to the printing point and also having means
for effecting a connection between the car-
riage and the oscillating mechanism.
- 15 49. In a typewriting machine, the combi-
nation with the carriage and escapement
shaft, of a toothed wheel actuated from said
shaft, typewriting mechanism shiftable into
the path of said toothed wheel, and means
20 for adjusting the relation of said typewrit-
ing mechanism to said toothed wheel, where-
by to regulate the speed of the carriage.
50. In a typewriting machine, in combi-
nation, a main type bar system, a power
driven releasable carriage, escapement de-
vices for the carriage, a toothed wheel actu-
ated by the movement of the carriage when
the same is released from its escapement de-
vices, and auxiliary typewriting mechanism
actuated by said toothed wheel, whereby in-
termittently to resist the free run of the
carriage and thereby control the writing ac-
tivity of said mechanism. 25
51. In a typewriting machine, the combi-
nation with a main type bar system and a 30
power driven carriage, of auxiliary type-
writing mechanism actuated by the move-
ment of the carriage in the direction of its
feed, said mechanism including a toothed
wheel whereby to render said movement in-
termittent. 35

In testimony whereof I affix my signature
in presence of two witnesses.

GEORGE VOELKER.
